[57] CLAIM

The ornamental design for a transvaginal probe for use in pelvic scanning or the like, as shown as described.

DESCRIPTION

FIG. 1 is an elevational view of a transvaginal probe for use in pelvic scanning or the like, showing my new design, the broken line showing of the power cable being for illustrative purposes only and forming no part of the claimed design;

FIG. 2 is a rear end elevational view thereof, taken in the direction of line 2—2 of FIG. 1; and

FIG. 3 is a front end elevational view thereof.
